CONTROL DEVICE FOR HEATING APPARATUS

Filed Sept. 22, 1926

UNITED STATES PATENT OFFICE

LEWIS W. EGGLESTON, OF CLARENCE TOWNSHIP, ERIE COUNTY, NEW YORK, ASSIGNOR
TO AMERICAN RADIATOR COMPANY, OF NEW YORK, N. Y., A CORPORATION OF NEW
JERSEY

CONTROL DEVICE FOR HEATING APPARATUS

Application filed September 22, 1926. Serial No. 137,116.

My invention relates to new and useful improvements in control devices for heating apparatus, and more particularly to devices of that general character or type which is responsive to a variation of liquid level in a heating apparatus, for example, the water level in a boiler, to regulate the rate of combustion in the heating apparatus.

While the invention is capable of wide use for the control of combustion in a heating apparatus, it will be found particularly useful for controlling the combustion of an oil burner applied to a heating apparatus. For example, it may be employed to control a supply of oil, or a supply of air and oil, to an oil burner, and to stop such supply when the water level in the boiler falls below a predetermined point of safety.

The invention may also include a device not only for control in response to a variation of liquid level, but which may also respond to variations of pressure in the heating apparatus, for example, steam pressure in a boiler, so as to control or regulate combustion in the heating apparatus.

The invention consists in the improvements to be more fully described hereinafter, and the novelty of which will be particularly pointed out and distinctly claimed.

In the accompanying drawing I have fully and clearly illustrated a preferred embodiment of my invention, and in the drawing Fig. 1 is a vertical central sectional view showing certain of the parts in elevation;

Fig. 2 is a section on the line 2—2 of Fig. 1, and

Fig. 3 is a detail plan view of a lever member.

Referring to the drawing by characters of reference, 1 designates a hollow casing having a float chamber 2 with a hollow cylindrical column 3 communicating therewith and extending vertically upward therefrom. At its lower end the chamber 2 is provided with a threaded nipple 4 adapted to be connected by a suitable pipe, not shown, with the water-containing space of a boiler at a point below the normal liquid level in the latter. At the head of the column 3 is a nipple 5 adapted to be connected by a pipe, not shown, to the liq-

uid-containing space in the boiler at a point above the normal liquid level therein. The arrangement is such that the device may be applied to a boiler in such position that there will be a liquid level within the device corresponding to the level in the boiler.

The column 3 may be provided with upper and lower threaded nipples 6, 7, to which may be attached the upper and lower connections of any well known form of gauge glass, not shown, to indicate visually the liquid level within the hollow casing and the boiler.

The float chamber 2 is provided at one side with a flange or hollow extension 8 which opens into and receives a substantially L-shaped hollow fitting 11 with a flange 9. Between the flanges 8 and 9 is a gasket 8^a which effectively seals the joint against leakage. Bolts 10, preferably four in number, pass through flange 9 into threaded sockets in flange 8 to fasten said fitting to the chamber 2. The upturned portion or extension 12 of fitting 11 has bolted thereto a flange 13 on the lower end of a hollow coupling member 14. The coupling member 14 is provided with spaced depending ears 15, which are adapted to extend downwardly within the portion 12 of fitting 11 and which carry a cross-pin 16.

Upon the pin 16 is mounted a combined rocking and thrust element, preferably in the form of a bar or rod 17, which is provided at a point intermediate its ends with a longitudinal slot 18 to receive said pin 16 upon which the rod 17 may fulcrum. The slot is made of a width substantially the same as the diameter of said pin, but said slot is of a greater length than the diameter of said pin 16. The element 17 may not only rock on the pin 16 but is also capable of a sliding or reciprocating movement thereon, limited by the end walls of the slot 18. Near its lower end the rod 17 is formed with a circumferential abutment, preferably in the form of a shoulder 19. An annular plate or head 20 having a central opening 20^a is positioned on rod 17 and is held thereon by means of a collar 21, said collar and plate being clamped in position by a nut 22 threaded on the lower end of said rod. The collar

21 is formed with a radial socket 23 which receives and holds one end of an arm or rod 24 which extends through the fitting 11, and a vertical slot 24^a cut in a plate 25^a, which 5 slot serves as a guide means for said rod. The plate 25^a is fixed to the flange 9 by any well known means, and extends across the opening between flange 8 and fitting 11. The opposite end of the said rod 24 has secured 10 thereto, as at 25, by means of a set screw or the like, a float 26, which is located in the float chamber 2 formed by the casing 1. It will be seen that the float will be responsive to variations of liquid level within the chamber 2, and when moved will operate through 15 the arm 24 to rock the rod 17 upon its fulcrum 16.

Hermetically sealed, as at 27, to the edge 20 of the plate 20, is the lower end of a diaphragm, preferably of metal, and in the form of a cylindrical corrugated expandable-collapsible element or bellows 28. The upper end of the element 28 is also hermetically sealed, as at 29, to the inner edge of an annular plate 30, the outer edge portion of which is clamped, as at 31, in a recess 12^a in extension 12 and between the extension 12 and flange 13 heretofore described. The sealing means between the bellows 28 and 30 the plates 20 and 30 is preferably solder, but any suitable substance may be used. A fluid-tight joint is effected at 31, so that said bellows or diaphragm acts as a fluid-tight joint or packing closing the opening about 35 the rod 17 and through the upturned portion of fitting 11. It will also be seen that the diaphragm 28 and the head 20 are exposed to fluid pressure which may exist within the system which includes chamber 2 and the fitting 11, and will respond to such pressure to move the rod 17 upwardly with pin 16 riding in slot 18, the response to fluid pressure being controlled or regulated by means to be described hereinafter.

45 At its upper end the rod 17 acts upon a suitable thrust member 39 in order to transmit the motion initiated by movement of the float or by fluid pressure on the bellows, to a device controlled or operated thereby to effect a control at a remote point. For this purpose the upper end of the rod 17 is provided with a transverse axial open slot 32, which receives and holds a connecting plate 33 having an intermediate transverse edge 34 which seats against the base of said slot, and said plate is also provided with depending lugs 35 which extend downwardly from edge 34 and embrace the side portions of the rod 17 at points below said transverse slot. The 50 plate 33 is held rigidly in place in the upper end of rod 17 by the lugs 35, in conjunction with a transverse pin 36 which passes through rod 17 and plate 33. The upper end of the plate 33 is provided with an upwardly extending ear 37 which is located to one side

of the longitudinal axis of the rod 17. Pivoted on this ear, as at 38, and therefore offset from the longitudinal axis of rod 17, is the lower end of a thrust element, preferably in the form of the rod 39, which extends upwardly through the hollow coupling 14.

70 In the preferred embodiment of the invention herein shown and described, the controlling device to be actuated by the thrust member or rod 39, consists preferably of an electric switch which may be employed to make or break a circuit, or make and break a circuit for operating means, not shown, for controlling combustion, or other means, for example, a water supply valve for automatically supplying water to a boiler when the level drops below a determined point.

75 This switch may take a number of forms without departing from the scope of my invention, but in the preferred embodiment it includes a casing 40 supported upon the coupling 14 and having an opening 41 through which the upper end of the thrust member 39 projects. Within the casing 40 is a lever 42 fulcrumed on the casing, as at 43, and carrying a socket member 44 in which engages the pointed upper end 39^a of the thrust member 39, the arrangement being such that an upward movement of member 39 swings said lever 42 upward on its fulcrum from the position shown in Fig. 1, in which the forward end of the lever is depressed below its fulcrum 43. On the opposite side of the lever 41 from the plunger 39, is a socket bearing 45 which receives a pin 46 carried by a spring plate or seat 47 which supports the lower end of a compression spring 48, the opposite end of which engages a spring plate or seat 49. The spring plate or seat 49 is provided with a socket 50 in which is seated a polyfaced nut 51 threaded on an adjusting screw 52 which is fixed, as at 53, in the top wall of the casing 40 and extends axially of said spring 48. By adjusting the position of plate 49 on screw 52 the resistance of spring 48 to the thrust of element 39 may be regulated. The outer end of the lever 42 has pivotally connected thereto, as at 54, the lower end of a link 55, the upper end of which is pivoted, as at 56, to a 80 tilting support 57 fulcrumed at 58 in any suitable manner in the casing. The support 57 is provided with spring clips 59 which support a switch member 60. This switch member is preferably in the form of an evacuated glass tube 60^a provided with internal contacts 61 connected to circuit leads 62 in circuit with the device to be controlled (not shown). In the glass container 60^a is a body 85 of fluid-conducting material, for example, mercury, which when the tube is tilted in one direction, for example, that shown in Fig. 1, immerses the contacts 61 and forms an electric circuit through said contacts, thereby 90 completing the circuit through the leads 62 13

and the device (not shown) to be controlled—for example, an air supply fan, etc.

At its forward end the lever 42 is provided with a laterally extending transverse arm 63 fixed thereto, and which has an opening therethrough in which is mounted an internally threaded bushing 65. Threaded in this bushing and projecting forwardly of the transverse arm 63 and lever 42, is a screw 64 which has a pointed end 70, preferably conical in form. At a point in the casing 40 substantially diametrically opposite to the fulcrum 43, is a fixed pin 69. A differential spring 67 having cup-shaped engaging or follower plates 66 and 68 is positioned between the screw 64 on lever 42 and pin 69, with the screw and the pin being seated respectively in the follower plates 66 and 68. The spring 67 when so positioned, normally tends to expand and exerts a downward component of force on the lever 42 in conjunction with the compression spring 48. The tension of the spring 67 may be varied so that it will exert the desired downward component of force by adjusting the screw 64 in its bushing 65. A stop member 71 is fixed on the lever 42 and projects into the slot 72 in the casing 40 to limit the up and down movements of the lever 42.

This switch specifically forms the subject matter of my copending application, Serial No. 32,401, filed May 23, 1925, and it is therefore not believed necessary to describe the same in greater detail herein.

The device may operate by change of fluid pressure or by change of water level or by change of both fluid pressure and water level acting in conjunction.

When the fluid pressure in the chamber 2 and fitting 11 increases without any change in the vertical position of the float 26, as shown in Fig. 1, the pressure will act upon the diaphragm 28 and its head 20 to compress the diaphragm and raise the rod 17 with pin 16 riding in slot 18. The float 26 will remain in a substantially constant position so that as the rod 17 is raised, fixed points on the rod will move in arcs of concentric circles of which a determinable point in the float 26 will be the common center. Therefore, the upper end of rod 17 will move in an arc and be rocked counter-clockwise and carry with it the lower end of thrust member 39, which will increase or straighten out the angle between rod 17 and member 39 and cause the thrust member 39 to move upwardly and transmit the upward motion of the bellows 28 to the lever 42. Upward movement of lever 42, limited by stop 71 in slot 72, will operate through link 55 to tilt the tube 60* on its fulcrum 58 to flow the mercury away from contacts 61 and thus break the electric controlling circuit between contacts 61 and through leads 62. The downward force exerted by adjusting spring 48 and the down-

ward component of force exerted by differential spring 67 together oppose the upward movement of the bellows 28 and member 39. This differential spring 67 is so positioned, as above described with relation to lever 42, that any upward movement of the lever 42, though it compresses the spring 67, will nevertheless decrease the downward component or effective force exerted by spring 67 upon lever 42, due to the decrease in the angle of application of the downward component caused by the movement of the lever 42. The spring 48 is so adjusted by means of nut 51, that its increased tension as the lever 42 is raised, and therefore its downward force, is less than the decrease in the downward component of force exerted by spring 67, and there is a consequent decrease in the combined downward force exerted by springs 48 and 67. This results in a snap or quick action being imparted to the switch member 60, which is desirable for efficient action of mercury tube switches. Movement of the bellows by force of fluid pressure existing in chamber 2 and fitting 11 is opposed or resisted by the combined downward force exerted by the springs 48 and 67 acting on and through lever 42, so that said bellows will not be collapsed by fluid pressure to operate the controller until the force exerted by the fluid pressure is sufficient to overcome the resistance of said springs. By suitable adjustment of said nut 51 and pin 64 the amount or degree of resistant force exerted by said springs may be regulated, set or determined to prevent actuation of the controller by fluid pressure on the bellows until the force exerted by such fluid pressure reaches or builds up to a given or desired point or value, whereupon any increase of such fluid pressure in the system will overcome the spring resistance and cause actuation of the controller. It will thus be seen that the device may be set to respond to a given fluid pressure condition within the limits of effective adjustment of the resistance afforded by said springs. The spring 48 is adjustable in conjunction with spring 67 to determine the point at which the lever 42 will start to respond to the fluid pressure on the bellows and the adjustment of the differential spring 67 determines the point at which the complete operation or movement of said lever 42 takes place in order to actuate the circuit controller.

When the water level in the chamber 2 drops, the float 26 will move downward with it from the position shown in Fig. 1. The float pivots upon the fulcrum 16 and transmits its movement to the rod 17 which will rotate about the pin 16 in a counter-clockwise direction. As the rod 17 rotates, it will carry with it the lower end of the member 39 to effect a toggle action which will raise the member 39 and the lever 42 to compress the springs 48 and 67 and actuate the controlling device or switch 60.

It is evident that if a leak should occur in the boiler so that the water level dropped rapidly, and caused a sudden increase in the steam pressure, that the thrust member 39 would be moved upward by the simultaneous lowering of the float 26 and increase in fluid pressure acting upon the diaphragm or bellows 28 and sufficient to overcome the spring resistance, so that the switch member 60 would 10 be operated conjointly by the float and by the bellows.

What I claim and desire to secure by Letters Patent of the United States is:—

1. In a device of the character described, 15 a casing having a float chamber, a float in said chamber and responsive to variation of liquid level therein, a controller, a lever having a connection with said controller to move the same, a pin supported at the end of said lever 20 and extending lengthwise of said lever, means operatively connecting said float and said lever, fluid pressure-responsive means sealing said chamber and acting through said operating means to move said lever in one direction, a spring opposing said fluid-pressure 25 means and operable to move said lever in the opposite direction, and a second spring opposing said fluid-pressure means when in one position and having a rocking support at one 30 end and at its other end engaging said pin, said support being so arranged that the resistance of the second spring is reduced when said operating means moves said lever.

2. In a device of the character described, 35 a casing having a float chamber, a float in said chamber and responsive to variation of liquid level therein, a controller, a lever having a connection with said controller to move the same, means operatively connecting said float 40 and said lever, fluid pressure-responsive means sealing said chamber and acting through said operating means to move said lever in one direction, a spring opposing said fluid-pressure 45 means and operable to move said lever in the opposite direction, and a second spring opposing said fluid pressure means when in one position and having a rocking support at one end and at its other end engaging said lever, said support being so arranged 50 that the resistance of the second spring is reduced when said operating means moves said lever.

3. In a device of the character described, 55 a casing having a float chamber, a float in said chamber and responsive to variation of liquid level therein, a controller, a lever having a connection with said controller to move the same, a pin supported at the end of said lever 60 and extending lengthwise of said lever, means operatively connecting said float and said lever, fluid pressure-responsive means sealing said chamber and acting through said operating means to move said lever in one direction, and means engaging said pin to regu- 65

late action of said lever by said float and said pressure-responsive means.

4. In a device of the character described, 70 the combination of a casing having a float chamber, a float in said chamber and responsive to variation of liquid level therein, a controller, a lever having connection with the controller to move the same, means operatively connecting said float to said lever to move it in one direction, a spring opposing said float and operable to move said lever in the opposite direction, and a second spring opposing said float when in one position and having a rocking support at one end and at its other end engaging said lever, said support being so arranged that the resistance of the second spring is reduced when the said float acts to move said lever. 75

5. A device of the character described comprising a float chamber, a float in said chamber and responsive to variation of liquid level therein, a controller, means for transmitting motion from said float to said controller to cause actuation of the controller, fluid pressure-responsive means sealing said last-named means to the chamber and responsive to fluid pressure in said chamber to actuate said controller, resilient means resisting actuation of said controller by said pressure-responsive means, and means for setting the resistance of said resilient resisting means whereby said pressure-responsive means responds to a determined pressure condition in said chamber. 80

6. A device of the character described comprising a float chamber, a float in said chamber and responsive to variation of liquid level therein, a controller, a lever connected to said controller to operate the controller, means for transmitting motion from said float to said lever, fluid pressure responsive means sealing said last-named means to the chamber and responsive to fluid pressure in said chamber to actuate said controller through said means for transmitting motion to said lever, means resisting operation of said lever by said fluid pressure-responsive means, and additional means determining the point of operation of said controller by said fluid pressure-responsive means, said last-named means being adjustable to set the point at which said controller is operated by said lever. 100

7. A device of the character described comprising a float chamber having a side opening, a substantially L-shaped hollow fitting open at its ends, means securing said fitting to said chamber with one of said open ends in communication with said side opening, an annular plate secured and sealed to said fitting at the other of said open ends, a substantially cylindrical hollow expandable-collapsible resilient corrugated member having one end thereof sealed to said plate around the inner periphery thereof, a control means having a fulcrum support, a float in said chamber, a lever, means connecting said lever and said

control means, plunger means pivotally supported in said fitting and operable by said float, said plunger means extending through the aperture of said annular plate and having engagement with said lever to move the same, and a head for said resilient corrugated member secured to said plunger means and sealing the free other end of said resilient corrugated member.

10 8. In a device of the character described, a movable control device, resilient means exerting a force in opposition to movement of said control device, the opposing force of said resilient means increasing upon movement of

15 said control device, a second resilient means exerting a component of its force in opposition to movement of said control device, the opposing component of force of said second resilient means decreasing upon movement

20 of said control device, the opposing component of force decreasing at a greater rate than the increase of opposing force of said first resilient means whereby the combined opposing force of said first and said

25 second resilient means decreases upon movement of said control device, and actuating means operative on and exerting a force to move said control device, the force exerted by said actuating means decreasing upon move-

30 ment of said control device, the decrease in the combined opposing force of said first and said second resilient means being at a greater rate than the decrease of the force of said actuating means whereby said control device is

35 moved quickly by said actuating means throughout its range of movement.

9. In a device of the character described, a movable control device, a float chamber, a float in said chamber operatively connected to

40 said control device to move the same, resilient means acting on said control device to exert a force to resist movement of said control device by said float, the resisting force of said resilient means increasing upon movement of

45 said control device by said float, and a second resilient means acting at an acute angle on said control device to exert a component of force to resist movement of said device by said float, the resisting component of force

50 decreasing upon movement of said control device by said float, the resisting component of force decreasing at a greater rate than the increase of resisting force of said first resilient means, the force exerted by said float upon

55 said control device decreasing upon movement of said float, the force exerted by said float decreasing at a less rate than the decrease of the combined resistance of said first and said second resilient means whereby said float

60 moves said control device with a snap action through its range of movement.

In testimony whereof I have hereunto signed my name.

LEWIS W. EGGLESTON.
